CLAIM

I claim the ornamental design for a lockable removable attachable catalytic converter cage, as shown and described.

DESCRIPTION

FIG. 1 is a top, front and right perspective view of a lockable removable attachable catalytic converter cage showing my new design;

FIG. 2 is a right side elevation view thereof;

FIG. 3 is a top plan view thereof;

FIG. 4 is a left side elevation view thereof;

FIG. 5 is a bottom plan view thereof;

FIG. 6 is a front elevation view thereof;

FIG. 7 is a rear elevation view thereof;

FIG. 8 is a left, bottom and front perspective view thereof showing environmental items;

FIG. 9 is a top, front and right perspective view of a second embodiment of my design;

FIG. 10 is a right side elevation view thereof;

FIG. 11 is a top plan view thereof;

FIG. 12 is a left side elevation view thereof; and

FIG. 13 is a bottom plan view thereof;

FIG. 14 is a front elevation view thereof;

FIG. 15 is a rear elevation view thereof; and,

FIG. 16 is a left, bottom and front perspective view thereof showing environmental items.

The broken lines shown in the drawings illustrates the environment of the claimed design and forms no part thereof.

1 Claim, 10 Drawing Sheets
